UNITED STATES PATENT OFFICE.

JOHN ALDEN MACLEAN, OF HAMPTON, NEW JERSEY.

VAPORIZER.

Application filed December 16, 1924. Serial No. 756,188.

To all whom it may concern:

Be it known that I, JOHN A. MACLEAN, a citizen of the United States, residing at Hampton, in the county of Hunterdon and State of New Jersey, have invented certain new and useful Improvements in Vaporizers; and I do hereby declare the following to be a full, clear, and exact description of the invention, such as will enable others skilled in the art to which it appertains to make and use the same.

My invention consists in the novel features hereinafter described, reference being had to the accompanying drawings, which show one form in which I have contemplated embodying my invention, and some slight modifications thereof, selected by me for purposes of illustration, and the said invention is fully disclosed in the following description and claims.

In carrying out my invention, I provide a hollow shell or body having a steam dome on its upper end and an enlarged opening at its forward end, closed by a door, normally bolted to the shell or body and carrying the individual heating units, which are preferably in the form of a spiral tube or tubes, connected to manifolds secured to the door and extending into the interior of the shell or body and supported by the door, the said door being also provided with supporting rollers, and a track engaging a supporting roller on the interior of the shell or body, for maintaining the door and said heating units in vertical position when the same are drawn out of the shell or body for cleaning purposes. I also provide baffles above the heating units in said shell or body for collecting liquid particles which would otherwise be carried into the steam or vapor dome, the said baffles being provided with troughs for conveying the liquid collected by the baffles to the main body of liquid being treated within the shell or body, at points distant from the areas of ebullition or priming, so as to prevent liquid from being transported into the steam dome and thence through the escape pipe without having been first converted into steam or vapor. My invention also contemplates, in one form or embodiment of the same, the use of twin vaporizing units which involve an economy of construction and convenience of operation in that, by means of suitable pipe connections and control valves therefor, one of the twin vaporizers can be separated from the

other, to permit of the removal of the door thereof and the heating elements, for cleaning, without disturbing the continued vaporization in the other vaporizer of the twin element or unit. My invention also contemplates other features hereinafter more particularly pointed out.

Referring to the accompanying drawings, Fig. 1 is a front elevation of a single vaporizing unit embodying my invention.

Fig. 2 is a top plan view of the same.

Fig. 3 is a transverse vertical section of the single vaporizing unit showing the heating elements, and one form of baffle.

Fig. 4 is a longitudinal section on line 4—4 of Fig. 3.

Fig. 5 is a perspective view of a form of baffle which may be employed above the heating coils.

Fig. 6 is a partial front elevation of the shell with the front cover plate removed showing the form of baffle, illustrated in Figs. 3 and 4.

Fig. 7 is a partial sectional view similar to Fig. 4, showing the type of baffle illustrated in Fig. 6.

Fig. 8 is a perspective view of the baffle shown in Figs. 6 and 7.

Fig. 9 is a front elevation of a twin vaporizing unit.

Fig. 10 is a vertical transverse sectional view of the same.

Referring to the single unit vaporizer illustrated in Figs. 1, 2, 3 and 4; 1, represents the shell or body which is preferably formed of cast iron and provided with a suitable base, 2. This shell or body is provided at its upper end with an aperture, 3, communicating with a steam or vapor dome, 4, having an outlet aperture, 5, to which is connected the vapor pipe for conducting the steam or vapor to a condenser, or other suitable mechanism. The front wall of the shell or body is provided with a large aperture, indicated at 6, normally closed by a vertically disposed door, 7, secured to the shell or body by bolts or screws, or studs on shell in the usual manner, around the edges of the front opening, 6. This door, 7, is provided at its lower end with a supporting roller, or rollers, 8, secured to the door in any desired manner, as by brackets, 9, and adapted to support the door and the parts carried thereby, and to facilitate the forward movement of the door, the rolls, 8, may travel on the floor in front of the shell

or body, or upon a suitable metal track, if preferred. In order to maintain the door in vertical position at all times and prevent it from toppling rearwardly when drawn away from the shell or body, 1, I provide the door with an inwardly extending track, indicated at 10, which is preferably in the form of an angle or T in cross section, that is to say, it is provided with a downwardly extending 10 roller engaging flange and a horizontal flange projecting on one or both sides of the vertical flange. This track may be conveniently made of either wrought or cast metal, and is rigidly bolted to the door and 15 extends horizontally substantially perpendicularly to the door. The shell or body is provided preferably just inside of the front opening, 6, with a grooved roller, 11, carried by a bracket, 12, bolted or otherwise secured 20 to the shell or body, so that as the door is drawn out, the vertical flange of the track, 10, will engage the roller, 11, and support the door and parts connected therewith in 25 vertical position. The rear or inner end of the track, 10, is preferably provided with 30 downwardly extending stops or projections, indicated at 13, conveniently made by bending a portion of the horizontal flange of the track or rail downwardly, as shown, but 35 which may be made in any other desired manner so that said stop or stops will engage the roller and prevent the track from disengaging the same accidentally when the door is drawn forward, and will serve to 40 limit the outward movement of the door from the shell or body. I prefer to employ a T-shaped rail as the track rail, having horizontal flanges projecting on both sides of the central vertical flange as indicated in Fig. 3, so that any sediment which may be 45 collected on the track or rail will fall on the upper face of the horizontal flanges, thus insuring that the vertical flange which extends downwardly and the grooved roll will be protected against the deposit of sediment, 50 so that the portion of the tract which contacts with the grooved roll and the rail will always remain substantially clean and will be in condition for efficient action, but as 55 before stated, I may employ an angle track rail having a horizontal flange and a downwardly extending vertical roll engaging flange, if desired. By attaching the track to the door, 7, and causing it to engage a 60 guiding and supporting roller within the shell, it will be noted that when the track is pulled out the interior of the shell is substantially free and unobstructed in its lower part, so that it is very readily cleaned.

I prefer to employ as heating units, spiral coils of tubing, indicated at 14, and preferably formed of copper or other suitable metal, which will not be affected by the liquid to be vaporized. I also prefer to support the heating units from the door, by con-

necting them with the door, 7, so that they may be drawn forward therewith, and thereby removed from the interior of the shell or body, for the purpose of cleaning them when this becomes desirable. In the present instance I have shown the door provided with two upper manifolds, 15, and two lower manifolds, 16, each provided with threaded nipples to which the individual heating coils, 14, are connected by unions, said heating coils extending vertically from each manifold, 15, to the manifold, 16, beneath the same, the said manifolds and the heating units connected therewith being thus supported entirely from the front door, 7. The manifolds are preferably provided with rearwardly extending brackets, indicated at 17, and the upper and lower manifolds are connected by vertical brace rods, 18, provided with nuts, 19, above and below the brackets, 17, as indicated in Fig. 4, so as to brace the manifolds and relieve them from strain due to the expansion and contraction of the heating units. It will be understood that the spiral structure of the heating coils or units, 14, permits them to accommodate themselves to variations in temperature. The upper manifolds, 15, are connected on the exterior of the door, 7, by a transversely extending intake manifold, 20, to which may be conveyed steam for furnishing the necessary heat to the heating units from any desired source of supply and the lower manifolds, 16, are connected by a transversely extending outlet manifold, 21, on the outside of the door, 7, for conveying away the condensate. I may employ any desired number of heating units or coils, 14, which may be found desirable, according to the size and capacity of the shell or body. In the present instance I have shown these heating coils arranged between the manifolds, 15 and 16, in pairs, side by side, five pairs of heating coils or units being connected between each manifold, 15, and its manifold, 16, and spaced at different distances from the door, 7, towards the rear of the shell or body, but I do not limit myself to this exact arrangement.

Above each rearwardly extending series of heating units within the shell or body I provide a suitable baffle or baffles, interposed between the upper portion of the shell or body and the steam dome, and preferably above the areas of ebullition or priming, which will naturally be directly above the several heating units or coils. In Fig. 5 I have shown one form of baffle two of which may be arranged side by side, each comprising an upwardly curved metal plate, 22, having its edges curved inwardly and upwardly, as at 23, to form troughs, 24, extending along the longitudinal edges of the baffles, the said baffles, 22, being placed closely adjacent to each other so as to prevent the passage of

liquid between them and said baffles, and said troughs being inclined longitudinally, preferably downwardly from rear to front of the shell or body. These baffles may be supported in any suitable manner within the casing, preferably by brackets secured to the walls of the shell or body. Obviously as the vapor rises above the liquid level in the shell or body it will pass into the baffles and thence around the upper end thereof to the steam dome, and any water particles carried by the vapor or condensed therefrom will follow the curvature of the baffles, 22, and find its way into the troughs, 24, along which the collected liquid will flow to the front end of the baffles, where it will fall into the liquid at points distant from the areas of greatest ebullition, or priming. In some instances I may employ a secondary baffle in the steam dome, as indicated in Figs. 3 and 4, comprising a truncated cone, 25, surmounted by cap, 26, of larger diameter than the opening at the upper end of the truncated cone, secured to the latter below its upper end and provided with lateral apertures, indicated at 27, for further deflecting the vapor and effecting the deposit of any liquid which may pass the baffles, 22, so that only vapor reaches the upper portion of the steam dome and passes off through the aperture, 5, to the conducting vapor pipe (not shown).

In Figs. 3, 4, 6, 7 and 8, I have illustrated a different form of baffle which consists of a horizontal plate, 32, having its lateral edges bent downwardly, as at 31, then inwardly, as at 30, and upwardly, as at 33, to form lateral troughs, 34, extending longitudinally of the baffle. In this form of baffle it is made of sufficient width to extend above two series of heating units, and is therefore provided with a central, vertical partition, indicated at 35, having similar troughs, 36, arranged at each side of said partition at its lower edge, and extending longitudinally of the baffle plate, 32, to which the upper edge of the partition may be connected by rivets or otherwise. This baffle plate is also provided with a back piece, indicated at 37, provided with transversely disposed trough sections, 38, extending downwardly from the central portion of the back piece to its lateral edges, where the transverse troughs, 38, empty into the lateral troughs, 34, as clearly shown in the drawings. This baffle plate is secured in position within the shell or body by means of a screw, or screws, 39, adjacent to the front orifice of the shell or body, and a suitable bracket, 40, secured to the rear end of the baffle plate and the rear wall of the shell or body, in any desired manner. The baffle plate, 32, is preferably so arranged that its top portion inclines downwardly from front to rear of the shell or body, that is, towards the back plate, 37, while the troughs, 34 and 36, incline downwardly from the back plate toward the front of the shell or body, where they discharge the collected liquid into the main body of liquid within the shell or body at points distant from the areas of ebullition or priming.

In Figs. 9 and 10 I have illustrated a duplex or twin vaporizing unit in which the shell or casing, indicated at 1^a, is provided with two compartments separated by a vertical partition, 50, each of said compartments being of substantially the same size and conforming in all respects to the shell or body illustrated in Figs. 1 to 4 inclusive. The casing, 1^a, is provided with two steam domes, 4^a, and each compartment is provided with the front opening, 6^a, normally closed by detachable door or plate, 7^a. The interior construction of each of these compartments including the heating units, baffles, manifolds, etc., are exactly the same as have been heretofore described with reference to the preceding figures, it being understood that I may employ either the form of baffles shown in the said Figs. 1 to 4, or the form of baffles shown in Figs. 6, 7 and 8. The several parts shown in Figs. 9 and 10 which are identical with those shown in Figs. 1 to 4 inclusive, are given the same reference numerals with the letter "a" added. In Fig. 9 I have shown the inlet manifolds connected with a common supply pipe, indicated at 51, the branch pipes being controlled by separate valves, 52 and 53, and in like manner I have shown the steam domes connected to a common vapor delivery pipe, indicated at 54, the branch pipes being controlled by independent valves, 55 and 56. In this twin construction it will be readily seen that an economy of operation is effected, as there will be no loss of heat when both of the units of the twin construction are in operation, at their contiguous points, as any differences in temperature within the separate chambers of the twin units will be exchanged from one chamber to the other through the partition wall, 50, instead of being radiated to the atmosphere, as would be the case where two entirely separate single units were employed. The twin unit is also extremely convenient in operation, as by closing the appropriate valves controlling the steam inlet to and vapor outlet from one unit, the front door or plate, 7^a, thereof may be removed and drawn out, together with the heating units in the manner previously described with reference to Figs. 1, 2, 3 and 4, to facilitate cleaning the interior of the chamber and the heating coils without interfering with the continuous operation of the other chamber, which will continue to function so that vaporization may be carried on continuously while one or other of the chambers of the twin unit is

open when necessary for cleaning or repair. It will be understood that each of the front doors, 7^a, will be provided with the supporting track, 10^a, having the stop, 13^a, and the 5 interior supporting roller, 12^a, as previously described with reference to Figs. 1 to 4.

In the operation of my improved vaporizer it will be understood that the liquid to be vaporized is introduced into the interior 10 of the shell or body by means of suitable pipes, 60, Figs. 1, 2, 3 and 4, for example, and may be fed thereto continuously if desired. Steam from any suitable source is admitted to the heating units through the 15 exterior and interior manifolds, before described, thus imparting heat to the liquid under treatment and vaporizing the same. The vapor as it rises comes into contact with the baffles, depositing any liquid particles carried thereby or condensed therefrom, and passing around the baffles, ascends into the steam dome, from which it is delivered by suitable pipe to a condenser. My 20 improved vaporizer is admirably adapted for the purpose of distilling sea water on vessels, for the production of pure water for boiler feeding, and other purposes, although it may be used for the vaporization or distillation of any liquid, for which it may be 25 found to be convenient or desirable.

What I claim and desire to secure by Letters Patent is:—

1. A vaporizer comprising among its members, a shell having an opening therein, 35 a door detachably secured over said opening, a heating element mounted on the door, roller supporting means for the door located outside of the shell, a horizontal track rigidly secured to the inner face of said door 40 and projecting through said opening into the interior of the shell, and a track support within said shell for movably engaging said track when the door is moved away from the shell.

45 2. A vaporizer comprising among its members a shell having an opening therein, a door detachably secured over said opening, a heating element mounted on the door, roller supporting means for the door located outside of the shell, a horizontal track rigidly secured to the inner face of said door 50 and projecting through said opening into the interior of the shell, a support for movably engaging said track, located within said shell and a stop on said track for limiting the outward movement of said track and door.

60 3. A vaporizer comprising among its members a shell having an opening therein, a door detachably secured over said opening, a heating element mounted on the door, roller supporting means for the door located outside of the shell, a horizontal track rigidly secured to the inner face of said door 65 and projecting through said opening into

the interior of the shell, said track being provided with a vertically disposed flange member and a horizontally disposed flange member adjacent to the upper edge of the vertical flange member, and a supporting 70 roller rigidly secured within the shell adjacent to said opening therein, and engaging the vertical flange member of said track.

4. A vaporizer comprising among its members a shell having an opening therein, 75 a door detachably secured over said opening, a heating element mounted on the door, roller supporting means for the door located outside of the shell, a horizontal track rigidly secured to the inner face of said 80 door and projecting through said opening into the interior of the shell, said track being provided with a vertically disposed flange member, and a horizontally disposed 85 flange member above said vertical flange member, a guiding and supporting roller rigidly supported within the shell adjacent to the said opening therein, portions of the horizontal flange member, at the inner end of the track, being bent downwardly to form 90 a stop to limit the outward movement of the track and door.

5. A vaporizer comprising among its members a shell having an opening therein, 95 a door detachably secured over said opening, a heating element mounted on the door, a T-shaped track rigidly secured to the inner 100 face of said door, and extending through said opening into the interior of the shell, a grooved roller and a supporting bracket therefor secured to said shell within the same adjacent to the said opening and engaging the vertical flange of said T-shaped track, whereby the horizontal flanges of said track 105 will protect the vertical flange thereof and said roller from deposited solid matter.

6. A vaporizer comprising among its members a shell having an opening therein, 110 a door detachably secured over said opening, a heating element mounted on the door, a T-shaped track rigidly secured to the inner 115 face of said door, and extending through said opening into the interior of the shell, a grooved roller and a supporting bracket therefor secured to said shell within the same adjacent to the said opening and engaging the vertical flange of said T-shaped track, whereby the horizontal flanges of said track 120 will protect the vertical flange thereof and said roller from deposited solid matter, portions of the horizontal flanges of said T-shaped track adjacent to the inner end thereof being bent downwardly into substantially vertical position on opposite sides of the vertical flange, into position to engage said supporting roller and limit the outward movement of the track and door.

7. A vaporizer comprising among its members a shell, heating elements located 125 therein, a baffle plate supported in said shell 130

67 above the heating elements and provided with inclined troughs for returning the liquid collected thereby, to the liquid within the shell at points outside of the zone of the 65 heating elements and distant from the areas of greatest ebullition.

8. A vaporizer comprising among its members, a shell, heating elements located therein, a baffle plate supported in said shell 10 above the heating elements, said baffle plate having downwardly extending lateral portions provided with inclined troughs on their inner faces for returning the liquid collected thereby to the liquid in the shell at 15 points outside of the zone of the heating elements and distant from the areas of greatest ebullition.

9. A vaporizer comprising among its members, a shell, heating elements located 20 therein, a baffle plate supported in said shell above the heating elements, said baffle comprising a transversely curved plate having its lateral edge portions extending downwardly from its central portion and bent inwardly and upwardly to form channels, said 25 baffle plate and said channels being inclined so as to return liquid collected thereby to the liquid in the shell at points outside of the zone of the heating elements and distant 30 from the areas of greatest ebullition.

10. A vaporizer comprising among its members, a shell, heating elements located therein, a baffle plate supported in said shell 35 above the heating elements, said baffle consisting of a plate curved transversely and having its lateral edges extending downwardly from its central portion and bent inwardly and upwardly to form lateral troughs, and a back plate provided with a 40 trough on its inner face discharging into one of the lateral troughs said lateral troughs discharging at points outside the zone of said heating elements.

11. A vaporizer comprising among its 45 members a shell, heating elements located therein, a baffle plate supported in said shell above the heating elements, said baffle consisting of a plate curved transversely and having its lateral edges extending downwardly from its central portion and bent inwardly and upwardly to form lateral troughs, and a back plate provided with 50 transversely disposed troughs extending downwardly from the central portion of the plate and discharging into said lateral troughs, said lateral troughs discharging at 55 points outside the zone of said heating elements.

12. A vaporizer comprising among its 60 members, a shell, heating elements located therein, a baffle plate supported in said shell above the heating elements, said baffle consisting of a transversely curved plate having its lateral edges extending downwardly from

its central portion and provided on their inner faces with lateral troughs and a longitudinal central vertical partition depending from the central portion of said plate and provided on opposite sides of its lower edge with troughs, said troughs discharging at 70 points outside the zone of said heating elements.

13. A vaporizer comprising among its members a shell, heating elements located therein, a baffle plate supported in said shell 75 above the heating elements, said baffle consisting of a transversely curved plate having its lateral edges extending downwardly from its central portion and provided on their inner faces with inclined lateral 80 troughs and a central vertical partition depending from the central portion of said plate and provided on opposite sides of its lower edge with troughs parallel to said lateral troughs, and a back plate provided with transversely disposed inclined troughs 85 communicating with the said lateral troughs, said lateral troughs discharging at points outside the zone of said heating elements.

14. A vaporizer comprising among its members, a shell provided with two compartments separated by a partition, of heat conducting material, each of said chambers having a front opening therein, a door detachably secured over each of said openings and provided with roller supporting means exterior to the shell, a heating unit secured to each of said doors, a supporting track secured to each of said doors and projecting into the interior of the shell, track 100 supporting and guiding means for movably engaging one of said tracks located within each chamber, means for supplying steam to the heating unit of each chamber, a steam dome for each chamber provided with a vapor outlet, and independent valves for controlling the steam inlet and vapor outlet of each chamber, whereby, by closing certain 105 of said valves, the door of one chamber may be removed with the heating unit therefor, without interrupting the vaporizing in the other chamber.

15. A vaporizer comprising among its members, a shell provided with a central vertical partition formed integrally therewith and dividing the shell into two chambers, each of said chambers being provided with a front opening, a door detachably secured to said shell over said opening, a heating unit supported by each of said doors 115 and extending into the adjacent chamber, means for supplying steam to both of said heating units, a separate steam dome for each chamber provided with a vapor outlet, and independent valves for controlling the 120 vapor outlet and steam supply for each chamber, whereby the door and heating unit of one chamber may be withdrawn for clean- 125

ing the said chamber, and the heating unit therefor, without disturbing the other chamber.

16. A vaporizer comprising among its members a shell having an opening in one of its vertical walls, a heating element normally supported within said shell, a door detachably secured to said shell over the said opening, a horizontally disposed track

rigidly secured to the inner face of said door and movable therewith, and extending through the said opening in to the interior of said shell, and a track supporting device supported within said shell and movably engaging said track.

15 In testimony whereof I affix my signature.

JOHN ALDEN MACLEAN.
